(74) Attorney, Agent, or Firm — Keisling + Pieper PLC;
Daniel B. Pieper(57) **CLAIM**

The ornamental design for a folding chair, as shown and described.

DESCRIPTION

FIG. 1 is a perspective view of a folding chair showing my new design;

FIG. 2 is a top view thereof;

FIG. 3 is a left side view thereof;

FIG. 4 is a front view thereof; and,

FIG. 5 is a right side view thereof; and,

FIG. 6 is a bottom view thereof.

The broken lines showing the screws and connectors are for the purpose of illustrating environmental structure and form no part of the claimed design.

1 Claim, 6 Drawing Sheets*FIG. 1*

FIG. 2

FIG. 3

FIG. 4

FIG. 6
